Furnace Company, Pittsburgh, Pa., a corpora-
tion of Delaware

Application December 17, 1937, Serial No. 180,336

2 Claims. (Cl. 263—15)

This invention relates to a furnace, in particular to a furnace of the so-called regenerative type in which fuel is supplied from one side and combustion products taken off at the other side during one period, and the direction of firing reversed during a succeeding period. The invention will furthermore be described herein with reference to a soaking pit furnace although it may be applied as well to furnaces of other types.

It has long been realized that in the operation of regenerative soaking pit furnaces, fuel of low calorific value has an advantage in that it is less likely to cause washing or melting of the ingot surfaces than is fuel of higher thermal content because such washing or melting introduces the necessity of chipping surfaces of the ingots to remove these defects. On this account blast furnace gas has been widely used for firing soaking pit furnaces.

I have invented a furnace and method of operating the same which secures the advantage of fuel having a low heat content in furnaces fired with fuel having a relatively high heat content.

In accordance with my invention, I divert a portion of the combustion gases flowing from the furnace toward the stack and return them to the side of the furnace on which fuel is being supplied. After passing through the regenerator on the side with the air supplied for combustion, the air and combustion gases are mixed with the fuel and combustion occurs in the soaking pit proper.

A present preferred embodiment and practice of the invention is illustrated in the accompanying drawing and a complete understanding thereof may be gained from the following detailed description. In the drawing:

The single figure is a diagrammatic view illustrating a regenerative soaking pit furnace and the connections therefrom to fuel and air supply means and to a stack for discharging waste gases.

Referring in detail to the drawing, a regenerative soaking pit furnace 10 comprises a pit proper, indicated at 11, and regenerators 12 and 13. Fuel supply ports 14 are disposed between the regenerators and the pit proper and are connected by suitable piping indicated generally at 15, to a convenient source of fuel. The fuel supply to the ports 14 is controlled by a regulating valve 16 and reversing valves 17 and 18.

Flues 19 and 20 extend from the regenerators 12 and 13 to a stack flue 21 communicating with the stack indicated at 22. Reversing valves 23 and 24 in the flues 19 and 20 permit either regenerator to be connected to the stack 22.

Air for combustion is supplied to the regenerator opposite that which is connected to the flue, by a blower 25 through piping 26 communicating with the flues 19 and 20. A regulating valve 27 and reversing valves 28 and 29 control the supply of air to the regenerators. A diversion flue 30 extends from the flues 19 and 20 adjacent the point where they join to an interconnecting flue 31, extending between flues 19 and 20. A blower 32 is disposed in flue 30 and is effective to draw waste gases from the flues 19 and 20 and divert them to the interconnecting flue 31. Reversing valves 33 and 34 are located in the flue 31, making it possible to direct the diverted waste gases toward the regenerator on the side of the furnace 15 at which fuel is being delivered.

With the various control and reversing valves in the positions indicated, fuel is supplied to the ports 14 between the regenerator 13 and the pit 11. At the same time, air is delivered by blower 25 through valves 27 and 29 and the flue 20 to the regenerator 13. The air is heated by passing through the regenerator and, as it mixes with the fuel supply through the ports 14, combustion occurs in the pit 11. Combustion gases flow through the regenerator 12, the flues 19 and 21 to the stack 22, since the valve 23 is open and the valve 24 closed.

As indicated by the arrows 35, a portion of the waste gases flowing toward the stack 22 is diverted through the flue 30 by the blower 32 and delivered through the flue 31 to the flue 20, since the valve 33 is closed and the valve 34 is open. In this manner, the diverted portion of the waste gases is mixed with the air entering the regenerator 13 and ultimately with the fuel delivered through the ports 14. Both the air supplied by the blower 25 and the diverted portion of the waste gas supplied by the blower 32 are preheated to a temperature of approximately 2000° F. The fuel is admitted in finely divided streams, so that it mixes intimately with the air and waste gases before entering the pit. By this method I obtain high thermal efficiency and still preserve the desired temperature of the gases in the pit. The invention also makes it possible to maintain a large volume of gas flow through the furnace, which is desirable.

When the direction of firing the furnace is to be reversed, the valve 18 is closed and the valve 17 is opened. The relative positions of valves 23 and 24, 28 and 29, 33 and 34 are reversed. The same result as that already described ensues, except in the reverse direction.

The amount of waste gases diverted and recir-

culated through the furnace is preferably varied in accordance with the condition of the ingots being heated. This may be accomplished by suitable control valves or by varying the speed of the blower 32. When heating cold ingots, little or no waste gas need be recirculated since the danger of melting or washing is slight. As the temperature of the steel rises, the quantity of waste gases diverted from the stack for recirculation is increased. This method of operation provides relatively quick heating in the earlier stages when the rate of temperatures is rapid, dropping off as the temperature increases because of the recirculation of increased quantities of waste gases.

Although I have illustrated and described but a preferred embodiment and practice of the invention, it will be understood that changes in the construction and procedure disclosed may be made without departing from the spirit of the invention or scope of the appended claims.

I claim:

1. In a furnace, a combustion chamber, a regenerator on each side of said chamber, means for supplying fuel selectively to either side of said chamber, flues having one end connected together and the other extending to said regenerators and adapted to serve alternately as air-supply and waste-gas passages, means for selectively supplying air to said flues and means effective to divert waste gases from the connected ends of said flues to points intermediate the ends. 5

2. In a furnace, a combustion chamber, regenerators on each side thereof, flues leading from said regenerators to a common discharge point, means for supplying fuel and air selectively to either side of said chamber, reversing valves in said flues between said point and said regenerators, and by-passing flues extending from said point to points in said first-mentioned flues intermediate said valves and said regenerators. 10 15 20
